UNITED STATES PATENT OFFICE.

ALVAH C. ROEBUCK, OF PARK RIDGE, ILLINOIS, ASSIGNOR TO WOODSTOCK TYPEWRITER COMPANY, OF WOODSTOCK, ILLINOIS, A CORPORATION OF ILLINOIS.

RIBBON HOLDER AND VIBRATOR.

1,275,755.

Specification of Letters Patent. Patented Aug. 13, 1918.

Application filed March 13, 1916. Serial No. 83,719.

To all whom it may concern:

Be it known that I, ALVAH C. ROEBUCK, a citizen of the United States, residing at Park Ridge, in the county of Cook and State of Illinois, have invented certain new and useful Improvements in Ribbon Holders and Vibrators, of which the following is a specification.

This invention relates to typewriter construction, but more particularly to that portion of typewriter mechanism by means of which the printing ribbon is held and reciprocated at each movement of the type bars. The invention consists in a novel construction, combination and arrangement of the parts.

The principal objects of the present invention are to produce a construction in which the parts need not be fitted so closely as in some other constructions; to effect a saving in time in the assembling of the parts by obviating close adjustments; and to provide a construction in which there is a minimum wearing of the parts, to prevent them from getting out of alignment.

In the accompanying drawings,—

Figure 1 is a plan view of a ribbon holder and vibrator constructed in accordance with the principles of my invention;

Fig. 2 is a side elevation partly in section of the parts shown in Fig. 1;

Fig. 2^a shows the upper end of the vibrator;

Fig. 3 is a detail view of the vibrator operating mechanism, and

Fig. 4 is a perspective of a spring clip attachment.

In a type of construction of the class to which this invention relates, and in which the vibrator lever was provided with an inclined slot with which the ribbon vibrator had engagement, it was possible under certain conditions to disengage the ribbon vibrator from the lever, especially when the vibrator and lever were in their uppermost positions, by taking hold of the ribbon vibrator and pulling it upwardly, the springing of the lower part being sufficient to allow it to become released from the lever. Also, by having the pin on the vibrator in engagement with a slot on the lever, the slot is at an angle to a horizontal line when the vibrator is in its uppermost and lowermost positions. This has a tendency to cause the joint pin in the bottom of the vibrator to slide up or down, as the case may be, making it impossible to hold the ribbon in perfect alignment; also if there were very much wear between these connecting parts, it would be difficult at all times, even with the closest adjustment obtainable, to hold the ribbon in proper alignment.

In order to overcome these difficulties, the conditions have been reversed; that is, the ribbon vibrator itself has been provided with a slotted member at the bottom thereof in which the slot is always held in a horizontal position, and engaging this slot is a pin carried by the vibrator lever, which, it is true, makes a sliding connection with the slot of the holder, but since the slot is always held in a horizontal position, the closest possible adjustment is always obtainable; there is no danger that the vibrator will slip or get out of alignment with respect to an inclined surface, and there is no possibility that the parts will become disengaged at either end or at any part of their movement.

Referring now more particularly to the drawings, the reference numeral 4 designates generally a ribbon holding member or ribbon vibrator with curved upper extremities 5, each provided with a ribbon engaging slot 6. At its lower end the holder is slightly bent, and formed integral therewith or rigidly attached thereto is a slotted member 7, so disposed that the slot 8 thereof extends in a horizontal direction. A brace or strengthening ridge 9 is formed at the bend of the vibrator to keep it in the position to which it is bent. It is understood, of course, that intermediate the ends of the vibrator 4 it is provided with a suitable guide for limiting the movement to an up and down reciprocating motion, the upper end of the vibrator being movable adjacent the front of a typewriter platen which is not shown in the drawings, as it is not necessary to the proper understanding of the present invention. A carriage shifting frame for the typewriter, comprising bars 10, 11 and a connecting bracket 12, is pivotally mounted about one of the bars 10 in a typewriter frame, and pivoted in the bracket 12 is a stud shaft 13 with an eccentric pin 14 at one end and a gear 15 attached to the shaft. Mounted on the stud shaft is a lever 16, and pivoted on one arm of the lever 16 is a ribbon vibrator lever 17, one end 18 of which has a pin 19 engageable in the

slot 8 of the member 7 attached to the ribbon vibrator 4. The other arm of this lever 17 is provided with a slot 20, which is engaged by the eccentric pin 14. Meshing with the 5 gear 15 attached to the stud shaft 13 is a gear 21, which may be rotated from the side of the typewriter shift frame and from the side of the typewriter itself, to vary the position of the eccentric pin 14 and thereby 10 to vary the position of the lever 17 and the ribbon vibrator 4, thus furnishing an adjustment for varying the position of the ribbon vibrator to utilize the full width of a ribbon carried thereby.

15 A spring clasp 7' with depending sides 8' which extend over the outer sides of slots 8 may be riveted to the lower end of the holder 4, as shown in Fig. 4, for convenience in assembling the parts and holding the pin 20 13 in position, if it is loosely connected to arm 18.

The ribbon vibrator lever 17 is oscillated by means of a universal bar 22 and a frame 23 to which it is attached, the universal bar 25 being engaged in the ordinary way by the movement of the printing type bars to the printing position, and the movement of the universal bar being given directly to the frame 23. Upturned from the frame 23 is a 30 bracket 24 in which a member 25 is pivoted. This member is formed with lateral projections 26, and the frame 23 is formed with corresponding bosses 27 in which screws 28 are threaded to engage the lateral 35 extending portions 26 to adjust the position of the pivoted member 25 with respect to the frame. Connecting the member 25 and the upper end of the oscillating lever 16, is a 40 adjusting screws 28 and the link 29. The pivoted member 25 are provided for accurately setting or varying the position of the oscillating lever 16 during assembly or subsequent adjustment of the machine, the vibrator lever 16 being moved horizontally by this adjustment, and the movement of the 45 oscillating lever 16 on the stud shaft 13 and with respect to the eccentric pin 14 causing an adjustment or variation of the vibrator lever 17 and a corresponding variation in 50 position of the vibrator 4, so that the vibrator can be made to assume a predetermined initial position, and a proper variation of throw of the vibrator can be obtained by the subsequent rotation of the stud shaft and its 55 eccentric pin from the side of the typewriter as above set forth.

The slotted member 7 at the lower end of the ribbon vibrator 4 is preferably in two spaced slotted portions, between which the 60 extremity 18 of the lever 17 is inserted, the bearing pin 19 being inserted through a proper aperture in the said end 18 and having a proper engagement with the slots 8 on both sides of the end 18. This produces a considerable bearing surface, which

is therefore less susceptible to wear than other constructions, and because of the construction of the parts the wearing is evenly divided and the connected parts are held in proper alignment and engagement with each other, without tendency to bend or buckle in either direction. The slots 8 of this member 7 are always in the horizontal position, and even if there is some wear between the pin 19 and the slots 8, there will be no difficulty 75 in adjusting or placing the ribbon and its holder 4 in any desired position; for by simply varying the position of the lever 17, the ribbon vibrator 4 can be raised or lowered by a direct vertical engagement of the 80 connecting parts, namely, a pin 19 and the horizontal slots 8. Therefore, no close adjustment of these parts is necessary in assembling the typewriter and these parts, for their position can be varied with absolute 85 certainty by the simple adjustment of the ribbon vibrator lever 17.

It is obvious, from the above description of the parts, that the actuation of the universal bar and its frame will cause the reciprocation of the ribbon vibrator; the oscillating lever 16 being attached to the shift frame which, although movable into upper or lower case position, is in either position fixed with respect to the frame 23, which is 90 oscillated as set forth by the printing type bars. The oscillation, therefore, of the member 25, which is connected by means of the link 29 to the lever 16, will cause the oscillation of the lower end of this lever 16 100 to which the vibrator lever 17 is pivoted.

I claim:

1. In an adjustable ribbon vibrator, the combination with a vertically reciprocable vibrator having a horizontal slot at the 105 lower end, and a horizontally adjustable vibrator lever having a pin on one arm engaging in the slot.

2. The combination with a vertically reciprocable and adjustable ribbon vibrator 110 having lower forked extremities with registering horizontal slots therein, a horizontally adjustable lever with one end extending between the extremities, and a pin fitting tightly in the lever and extending from 115 both sides thereof into the slots.

3. The combination of a vertically reciprocable ribbon vibrator formed of sheet material and having a lower extremity bent to extend horizontally with a strengthening ridge formed up out of the material at the bend and with the end bent to form a horizontal slot, and means to engage the horizontal slot for moving and adjusting the vibrator.

4. The combination with a reciprocable ribbon vibrator having a horizontal slot at its lower end, a horizontally reciprocable universal bar, and a horizontally and vertically adjustable vibrator lever actuated by 130

said bar and having a projecting pin which engages in the horizontal slot for accurately positioning the vibrator when the lever is adjusted.

5. The combination with a vertically reciprocal ribbon vibrator having a lower forked end with the extremities bent over to form registering horizontal slots, and a horizontally and vertically adjustable and

10 vertically oscillatable lever extending between the extremities and having a pin projecting from both sides thereof into the slots, the horizontal slot accurately defining the vertical position of the vibrator.

15 6. The combination with a ribbon vibrator having a forked end with registering slots in the extremities, a lever having an arm extending between the extremities, a pin extending through the arm into the 20 slots at both sides of the arm, and means extending over the outer sides of the slots to prevent disengagement of the pin.

7. The combination with a ribbon vibrator having a forked end with registering 25 slots in the extremities, a lever having an arm extending between the extremities, a pin extending through the arm into the slots at both sides of the arm, and a spring clip attached to the vibrator having portions to 30 extend over the outer sides of the slots to hold the pin in place.

8. The combination with a ribbon vibrator formed of sheet material with a forked 35 end bent at right angles to the remainder of the vibrator and the bend strengthened by a ridge and with the extremities of the fork bent over upon themselves to form closed registering slots, of an oscillatable lever fitting closely between said extremities, and a pin extending through the lever and into the slots at each side thereof.

9. The combination with a vertically reciprocal ribbon vibrator having a horizontal slot at its lower end, a vibrator lever 40 pivoted intermediate its ends and having a projecting pin at one end which engages in the horizontal slot for accurately positioning the vibrator, and an adjustable connection at the other end of the lever for varying 45 its position.

10. The combination with a vertically reciprocal ribbon vibrator having a horizontal slot at its lower end, a vibrator lever pivoted intermediate its ends and having a projecting pin at one end which engages 55 in the horizontal slot for accurately positioning the vibrator, a horizontally reciprocal universal bar, a variable pivotal support for said lever with an adjustment in connection with said bar, and means independent of said adjustment for varying the position of the other end of the lever.

11. The combination with a vertically reciprocal ribbon vibrator having a horizontal slot at its lower end, of a vibrator lever 60 having a pin at one end in engagement with the slot, a pivotal support for the lever intermediate its ends, means for engaging the other end of the lever to raise or lower the vibrator, and an adjustment for the pivotal 65 support for moving it in the direction of said slot.

12. The combination with a vertically reciprocal ribbon vibrator having a horizontal slot, of a vibrator lever having a pin 75 engaging in the slot, a universal bar frame, means for supporting the lever intermediate its ends comprising a second lever, an adjustable connection between the second lever and the frame for moving the vibrator lever 80 substantially parallel with the said slot, and an independently adjustable engagement for the other end of the vibrator lever for varying the vertical position of the vibrator.

13. The combination with a vertically reciprocal ribbon vibrator having a horizontal slot at its lower end, of a ribbon vibrator lever having a pin connection with said slot, means for adjusting the horizontal position of the lever and pin in the slot, 90 and separate means for adjusting the vertical position of the lever and said vibrator.

In testimony whereof I have signed my name to this specification, in the presence of two subscribing witnesses, on this tenth day 95 of March, A. D. 1916.
